ATTORNEYS.

UNITED STATES PATENT OFFICE.

RICHARD GIBBON, OF MOBEETIE, TEXAS.

SASH-FASTENER.

SPECIFICATION forming part of Letters Patent No. 338,837, dated March 30, 1886.

Application filed September 18, 1885. Serial No. 177,451. (No model.)

To all whom it may concern:

Be it known that I, RICHARD GIBBON, of Mobeetie, in the county of Wheeler and State of Texas, have invented a new and Improved 5 Sash-Fastening, of which the following is a full, clear, and exact description.

The object of my invention is to provide a new and improved device for holding a sash at any desired elevation, which device is 10 strong and durable and simple in construction and can be applied on any window.

The invention consists in the construction of parts and details and combinations of the same, as will be fully described and set forth 15 hereinafter, and pointed out in the claim.

Reference is to be had to the accompanying drawings, forming a part of this specification, in which similar letters of reference indicate corresponding parts in all the figures.

20 Figure 1 is a sectional plan view of my improved sash-fastening. Fig. 2 is a longitudinal sectional view of the fastening. Fig. 3 is a face view of the escutcheon. Fig. 4 is a side view of one of the side plates of the casing.

25 The casing A is provided with an end plate, B, and with two side plates or pieces, C, each having an upwardly-projecting lug, D, having a central opening, E, through which a squared spindle, F, can be passed freely, the 30 said spindle projecting from the front side of the window-casing G, and being provided with a knob, H. The spindle F is also passed through an escutcheon, J, fastened on the front of the window-casing G, and having a serrated or cogged opening, K, in its 35 center, into which a serrated or cogged part, L, of the spindle F at the knob H can be passed. A cross-pin, M, in the spindle F, behind the escutcheon J, prevents pulling the 40 spindle F out too far. The end plate of the casing A is provided with an opening, through which a sliding bolt, N, in the casing A can pass, on the upper edge of which bolt a rack, O, is formed, with which rack a pinion, P, 45 engages, the said pinion having collars P' on

the sides, which collars are passed into the aperture in the lug D to turn in the same. The sliding bolt N has a head, Q, on its outer end. The plate B is countersunk in the pulley-slide R, and the casing A projects into the 50 window-casing.

The operation is as follows: To hold the sash S at any desired elevation, the spindle F is pulled out until the serrated or cogged part L is withdrawn entirely from the escutcheon, 55 and then the spindle F is turned on its longitudinal axis in such a manner as to cause the pinion P to revolve in such a manner as to move and press the bolt-head Q firmly against the edge of the sash S. Then the spindle F 60 is pushed inward, and the part L is passed into the opening K in the escutcheon J, thus preventing the spindle F from revolving, whereby the bolt N is locked in place, and thus the sash is locked in place. To release 65 the sash the spindle F is withdrawn until the part L can clear the aperture in the escutcheon, and then the spindle is turned in such a manner as to withdraw the head Q from the sash S, which can then be moved up 70 and down freely.

One or two of the above-described devices can be applied to each sash.

Having thus fully described my invention, I claim as new and desire to secure by Letters 75 Patent—

The combination of the casing A, having apertured ears D, and a front plate, B, of the rack-bolt N, having a head, Q, beveled on its rear face to fit a corresponding beveled opening in the front plate, the pinion P, and the spindle F, the beveled head being adapted to enter the beveled opening of the front plate and lie flush with the outer surface of said front plate. 80

RICHARD GIBBON.
